BURNER FOR ANTHRACITE COAL

Ernest C. Webb, Portland, Oreg., assignor to Iron
Fireman Manufacturing Company, Portland,
Oreg.

Application October 31, 1931, Serial No. 572,332

4 Claims. (Cl. 110—45)

This invention relates generally to underfeed stokers, and particularly to a burner for anthracite coal.

The main object of this invention is the construction of a tuyère that will efficiently burn the small sizes of anthracite coal such as rice and buckwheat at a high combustion rate (number of pounds per square ft. of projected grate area) with a minimum amount of fly ash, and in 10 so doing to leave the ash in a loose unclinkered form so that it will drop freely from the sides of the tuyères with a minimum amount of clearance between the tuyères and the inner side of the furnace or boiler.

15 The second object is to provide a tuyère which will satisfactorily burn either buckwheat or rice sizes of anthracite coal without making any changes or adjustments for the different sizes, and also that it will be capable of efficient intermittent operation.

20 The third object is to so construct the tuyère elements that fine particles of coal or ash will not enter the air chamber and also that the construction will be relatively simple and inexpensive to manufacture.

25 Before entering into an explanation of this device it must be understood that it has long been the common practice to construct tuyère elements through which air could enter a retort from a plenum chamber in which the air was allowed to escape into the retort as best it might through all or a few of many openings, which are usually of considerable number, and this number has been increased to the utmost in an effort to get air up through the center of the fuel bed. However, due to the small horizontal area of the fuel bed below the combustion zone a relatively small amount of air can be forced through the voids in the fine sizes of coal at this 30 point.

35 Also due to the relatively large port area in many of the present styles of tuyères the velocity of the air leaving the tuyères is relatively low and the depth of its penetration into the fuel bed is not definite. With large sizes of coal this type of tuyère will penetrate with fair satisfaction, but with fine sizes of coal, to which this present invention relates, or in the presence of clinkers or semi-fused sections, the original direction of the incoming air is easily deflected since the air naturally takes the course of least resistance, which usually means by-passing a major portion of the fuel bed.

40 A further disadvantage constantly accompanying what will be referred to as the large port area

tuyère is that if a small section of the fuel bed temporarily opens up, due to a small clinker formation, a large volume of air rushes out of this section due to the fact that practically all of the resistance to the flow of air, namely by the fuel bed, 5 has been removed. Once a hole of this kind opens up it tends to stay open, due to the large volume of air, keeping the fuel blown out or burned out at this point, thereby further reducing the quantity of air delivered to the rest of the fuel bed.

10 Now if the major portion of the resistance to the flow of air is in the tuyère openings then a small change in the fuel bed resistance will have a relatively less effect on the total resistance, that is, of the tuyère and fuel bed combined, and the fuel bed will burn more uniformly with less fly ash, less clinkering and less excess air.

15 The problem then is to so admit the air to the retort, first, that it will have a maximum velocity 20 at its point of entrance; second, that the relation of the resistance to the flow of air through the tuyères and through the fuel bed be properly maintained; third, the relative positions of the points of admission; fourth, for the direction of 25 flow of injected air; fifth the general distribution of air, namely a few large openings or many small ones; sixth, the feeding of the fuel upwardly and uniformly over the entire area of the retort, and seventh keeping the tuyère ports open 30 and causing the burning fuels to remain in an unclinkered state until the residue passes over the edge of the retort.

35 These, and other objects, will become more apparent from the specification following as illustrated in the accompanying drawings, in which:

40 Fig. 1 is a vertical section through an anthracite burner equipped with an underfeed fuel supply and a clinker grinding mechanism.

Fig. 2 is a horizontal section along the line 2—2 in Fig. 1.

Fig. 3 is a perspective view of one of the tuyère rings.

Fig. 4 is an enlarged perspective view of the 45 pads positioned in the spaces between the tuyère rings.

Fig. 5 is an enlarged section along the line 5—5 in Fig. 1.

50 Fig. 6 is an enlarged section through a retort showing somewhat graphically on one side the relative volumes of air delivered at different elevations within the retort and also the relative shapes of the green coal zone, the burning zone and the ash zone.

Similar numbers of reference refer to similar parts throughout the several views.

Referring in detail to the drawings, there is shown a retort 10 through which fuel is fed by a feed screw 11 from a magazine (not shown). The retort 10 is connected to this magazine by means of a fuel feed duct 12 which passes through the setting 13. Surrounding the upper portion of the retort 10 is an internal gear 14 which is supported by a crusher ring 15 which is rotatably mounted within the crusher ring guard 16 at whose upper edge is secured an ash seal ring 17. A clinker arm 18 is secured to the crusher ring 15 by means of the screws 19.

Resting on the retort 10 is a retort ring 20 which is provided with an upwardly turned cylindrical wall 21 and an upwardly turned outer edge 22, which edge occupies a groove 23 in the crusher ring 15. The ring 15 is attached to the gear 14 by means of the bolts 24.

The parts 14 to 24 inclusive belong to the ash removing portion of the stoker and the operation thereof is well understood in the art.

Referring more particularly to my invention, which resides in the tuyère elements, it will be noted that upon the wall 21 rests a conical tuyère casing 25 and upon the raised rim 26 of the retort ring 20 rests the tuyère bottom ring 27. The inner face 28 is inclined approximately the same as the face 29 and is off-set slightly therefrom. The bottom ring 27 is held concentric with relation to the raised rim 26 by means of the downturned edge 30 formed around the outside of the bottom of the ring 27. The upper edge 31 of the face 28 is raised above the top side 32, and the face 33 of the raised edge 31 is inclined approximately at the same angle but opposite to the face 28. The corner 34 at the upper end of the face 29 is utilized to produce a cascading effect in the fuel passing upwardly from the retort. The top side 32 has formed thereon a series of raised pads 35, and the intervening spaces 36, in conjunction with the under side of the next ring above, form the tuyère outlet ports, the areas and positioning of which will be discussed later.

The tuyère second ring 37 is also inclined in shape and is provided with a step 38 similar to the corner 34. The lower side 39 of the second ring 37 rests upon the top faces of the pads 35. Obviously, the pads 35 could be incorporated on the under side of the ring as well as on the top side of the ring.

It will be noted that the face 40 is off-set from the face 41, and that the face 41 is off-set from the face 28. It will also be noted that any air which passes from the plenum chamber through the spaces between the pads 35 will be deflected upwardly, as shown graphically in Fig. 6, in which the numbers of lines of arrows correspond approximately to the relative volumes of air passing upwardly through the fuel, and while these arrows are indicated to show relatively straight lines it must be understood that this air will naturally be diffused and mingle with the air from other streams being injected into the fuel from other tuyère rings.

The second ring 37 is also provided with a raised edge 31 and pads 35 upon which rest the tuyère's third ring 42. This ring is provided with a pair of off-sets 43 similar to the off-set 38 and its lower edge rests upon the pads 35 of the second ring 37. The third ring 42 is also provided with a raised edge 31 and pads 35 upon which rest the tuyère's fourth ring 44. The

fourth ring 44 is also provided with a raised edge 31 and has a single sloping face 45 which slopes somewhat less than does the face 46 of the ring 42. The ring 44 is also provided with pads 35 upon which rests a tuyère top ring 47 whose top face 48 slopes less than does the face 45, and whose side 49 slopes downwardly to the horizontal portion 50 which is also provided with pads 35.

Around the top ring 47 is placed a retaining ring 51 which rests upon the pads 35 of the ring 47. The ring 47 has a downwardly extending flange 52 which is sealed within the recess 53 in the tuyère casing 25.

For the sake of clarifying the explanation the various air outlets will be numbered successively commencing with the bottom 54, 55, 56, 57 and 58 respectively, the first being between the rings 27 and 37 and the last between the members 47 and 51.

The operation of the device is as follows: The retort 10 having been designed to provide a uniformly upward movement of the fuel from the retort into the tuyère sections it will be assumed that a static head is maintained in the plenum chamber considerable in excess of that usually maintained in existing devices, and that the area of the spaces 36 is such that the restriction afforded thereby will permit approximately ten per cent of all of the air delivered to the combustion through the tuyères to pass through the outlet 54, and that fifteen per cent of all of the air delivered will pass through the outlet 55, and that twenty-five per cent of the air will pass through each of the three outlets 56, 57 and 58 respectively.

Now it will be noted in Fig. 6 that there is indicated in dotted lines a triangle whose base 59 is approximately at the outlet 55 and whose sides 60 are approximately equal to the length of the base 59. The lines 58 and 60 represent the outlines of what will be referred to as the cone of ignition. In this same figure there is represented by different cross hatched areas the ashes A, the burning coal B and the green coal C, which is well below the base line 59, and these coals while warm do not begin to burn until they enter the ignition cone.

It is well understood that there is no sharp line of demarcation between the zones since the transition is not instantaneous but gradual, and the illustration is made merely for the sake of facilitating the explanation of what transpires and the reasons therefor.

Attention is now drawn to the fact that the outlet 55 is well above the outlet 54; also that the outlet 56 is well above the outlet 55 and that each succeeding outlet 57 and 58 is definitely spaced above its next lower outlet. The reason for this spacing is as follows: If, as is commonly practiced, the openings are uniformly distributed over the burning face of the tuyères the active burning area is limited to the immediate vicinity of the tuyère face. The finer the coal the greater the degree of limitation. Due to the fact that the total heat release occurs over this limited area the temperature of the fuel in this area is necessarily raised to a point above the softening temperature of the ash in the coal and clinkers are formed. These clinkers are quite porous and allow a large portion of the air supplied through the uniformly distributed tuyère openings to be deflected through them instead of penetrating the fuel bed.

In other words, it may be considered that this

region of intense burning forms the clinkers, and when formed the clinkers tend to aggravate the condition by deflecting still more of the air through this small area. My object, then, is to admit the air to the fuel bed in a manner that active burning occurs over a larger portion of the retort at high combustion rates and with more complete burning of the fuel before being discharged over the side of the tuyère when operating at these high rates, and also that the stoker may be operated with a lower excess of air, and that whatever ash is formed and falls from the side of the tuyère is in a soft unclinkered state, thereby simplifying its further removal from the furnace and requiring a minimum clearance between the tuyère and furnace, or permitting a maximum burning area.

Again, when a large number of air openings are distributed over the tuyère there is a tendency to carry the fire down low into the retort. The coal passing along this face close to the tuyères remains in the heat burning zone a relatively long time before being discharged over the side, and in doing so it is burned completely before reaching the edge of the tuyère, and in this burned or clinkered form is very porous and allows a very large portion of the air to escape without doing much effective burning.

Again returning to the operation of my device, it will be remembered that the flow of air from the plenum chamber into the fuel bed is restricted at the tuyère outlet and that it is directly upward and inward in each instance from the outlets 54 to 58 inclusive, and also that air at a relatively high velocity is made to penetrate the fuel bed at the place and in the quantities needed, and also that the fuel is not only prevented from stopping the tuyère openings but is actually loosened in cascading past these openings keeping same in a loosened and aerated condition ideally adapted for the complete burning of the fuel at the lowest possible temperature, with the idea in mind of not forming hard clinkers which must otherwise be disposed of, and the reader cannot be too forcibly reminded of the fact that by placing the restriction at the tuyère outlet it is possible to have the air penetrate the fuel and therefore aerate same and hold it in readiness for the subsequent changes which take place from the moment the fuel is first heated until the time its incombustibles are delivered over the rim of the retort into the ash remover.

The result of this relationship may be stated in a few words, namely that the upward moving body of the smaller sizes of anthracite coal will be completely charged with air as it moves upwardly, and the rate of this charging will be directly proportional to the air-consuming requirements of the combustion at the various points of the burning surface.

It will be noted that this is quite the reverse of the practice commonly accepted in the burning of bituminous coal in which the flow of air is softened toward the rim of the combustion zone. In the present instance the volume increases toward the outermost portion of the burner and that only a relatively small stream is directed into the center of the fuel. This may be readily understood when it is remembered that only a small portion of the burning takes place in the center of the fuel and that the movement of the

fuel is directed as nearly as possible normal to the sides 60 of the cone of ignition, and that in this movement the fuel is further charged by air from the intersecting corners so that by the time each particle of coal or the remains thereof is ready to pass over the side of the ring 54 it has been subjected to the lowest possible burning temperature and for the shortest possible space of time consistent with the complete extraction of combustibles therefrom. 10

I claim:

1. A burner having circular superimposed tuyère elements forming an outwardly flaring fire pot, each adjacent pair of tuyère elements having substantially horizontal air passages 15 formed between same and the lowermost element of each pair having a continuous lip formed around the upper inner edge thereof which lip extends above the top of its respective horizontal air opening, said lip constituting a means for deflecting air streams upwardly and preventing the moving fuel from entering the tuyère openings. 20

2. An anthracite burner having in combination a plurality of superimposed circular tuyère elements forming a fire pot having an upwardly 25 and outwardly flaring rim, a plenum chamber surrounding said tuyère elements, said tuyère elements having a series of air grooves formed around the upper edge thereof, each of said tuyère elements having an annular flange projecting upwardly above the innermost top side of said air grooves, the total cross-sectional area of the openings formed by said grooves and the next tuyère element above at any one level exceeding the total cross-sectional area of the openings at 30 the next lower level, said openings constituting restricted passages whereby air may be maintained in the plenum chamber at a relatively high static head and delivered to the fuel in upwardly 35 directed penetrating streams of increasing volume toward the uppermost levels. 40

3. A burner for anthracite coal having in combination a retort provided with means for feeding coal uniformly upward therethrough, a plenum chamber surrounding said retort, a plurality 45 of superimposed tuyère rings mounted over said retort, each of said rings flaring outwardly and each having its uppermost edge projecting into the central opening of the next succeeding ring above forming a deflector, the joint between each pair of rings having air grooves formed therein below the top of the deflector, and communicating between said plenum chamber and the interior of the tuyère rings from which grooves air may be directed upwardly by 55 said deflector, and a fan for delivering air to all of said grooves at a uniform relatively high static head.

4. A burner for anthracite coal consisting of a plurality of superimposed circular tuyère rings, 60 each of said rings flaring outwardly, the top of each ring forming a support for the next ring above, the upper edge of each ring having an upwardly extending annular flange formed around its innermost side, the top side of each ring outside of said annular flange having air grooves formed therein and a plenum chamber surrounding said tuyère rings from which air may be delivered through the grooves in said rings into the 65 body of the fuel. 70

ERNEST C. WEBB.
